POWER TRANSMITTING MECHANISM

Joseph L. Underhill, Indianapolis, Ind., assignor
to Radio Corporation of America, a corporation
of Delaware

Application November 29, 1941, Serial No. 420,953

12 Claims. (Cl. 192—7)

This invention relates to power transmitting mechanism, and more particularly to a driving mechanism for the turntable of phonograph apparatus.

It is well known that turntables of phonographic apparatus are subject to variations in load over a substantial range. Thus, for example, in a machine adapted for both recording sound on a blank record and reproduction of sound from a finished record, the load upon the turntable when a record is being cut in the blank is greater than the load upon the turntable when a reproducing needle is tracking the groove of the finished record. This difference in load upon the turntable results in a difference in speed thereof which causes a variation in pitch between the sound as recorded and the same sound as reproduced.

The primary object of my present invention is to provide an improved turntable drive which will not be subject to the aforementioned disadvantage.

More particularly, it is an object of my invention to provide an improved turntable drive mechanism the speed of which will not vary appreciably over a wide variation of loads upon the turntable.

Another object of my invention is to provide an improved turntable driving mechanism as aforesaid which will insure a constant load on the driving motor.

It is also an object of my invention to provide an improved turntable driving mechanism as above set forth which is simple in construction, inexpensive in cost, easy to assemble, and highly efficient in use.

In accordance with my invention, I provide a motor having a driving pulley on its shaft and a rubber tired idler pulley interposed between the motor driving pulley and the rim of the turntable. Thus, the motor pulley drives the idler which, in turn, drives the turntable. The idler carries a brake drum and is floatingly mounted relative to a stationary brake member, a tension spring acting on the supporting member for the idler in such a manner as to pull the brake drum into pressing engagement with the brake shoe. When there is no load on the turntable, or when the load on the turntable is very light, the full tension of the spring acts on the idler to press the brake

drum hard against the brake, but when the load on the turntable is increased, the turntable reacts on the idler in such a way that it reduces the effect of the tension spring and the pressure between the brake shoe and the brake drum is reduced. Thus, the braking action on the idler, which has an inverse relationship to the turntable load, can be used to compensate for load variations on the turntable. By suitable selection of materials used for the brake surfaces, and by suitable design of the brake drum as to diameter, as well as the position or shape of the brake shoe, it is possible to maintain a constant load on the motor at the point of contact between its drive pulley and the idler pulley over a desired variation of loads on the turntable. Alternatively, it is possible for the load at the point of contact between the drive pulley and the idler pulley to either increase or decrease with an increase of turntable load. By arranging for the load at the aforementioned point of contact to decrease slightly as the turntable load increases, it is possible to compensate for the increased slippage at the point of contact between the idler and the turntable rim when the turntable load is increased.

The novel features that I consider characteristic of my invention are set forth with particularity in the appended claims. The invention itself, however, both as to its organization and method of operation, as well as additional objects and advantages thereof, will best be understood from the following description, when read in connection with the accompanying drawing, in which

Figure 1 is a fragmentary plan view of a phonograph employing a drive mechanism according to one form of my invention,

Figure 2 is a side elevation thereof, and

Figures 3, 4 and 5 are diagrammatic views illustrating the principle involved in the operation of a power transmission mechanism in accordance with this invention.

Referring more particularly to the drawing, wherein similar reference characters designate corresponding parts throughout, there is shown a motor board 1 carrying a bushing 3 in which is rotatably received the spindle of a turntable 5 having a peripheral flange or rim 7. The motor board 1 is also provided with an opening 9 through which extends the drive shaft 11 of a

suitable motor 13 fixed to the underside of the motor board 1. The motor shaft 11 is provided with a driving pulley 15 from which torque is transferred to the turntable 5 by a rubber-tired, preferably metal, idler pulley 17 interposed between and having engagement with the driving pulley 15 and the rim 7 of the turntable.

The idler pulley 17 is rotatably carried on the end of a supporting arm 19 which is pivotally mounted on a stud 21 carried by the motor board 1. Also fixed to the motor board 1 is a bracket or the like 23 to which is rigidly secured a brake member, such as a brake shoe 25, adapted to cooperate with a brake drum 27 which may be either formed integral with or secured to the idler pulley 17. The brake drum 27 is preferably of smaller diameter than the rubber tired idler 17. It will be noted that, by reason of the pivotal mounting of the supporting arm 19, the idler 17 and its brake drum 27 are floatingly supported relative to the brake shoe 25. A tension spring 29 having one end fixed to the motor board 1 and the other end secured to the supporting arm 19 constantly pulls the arm 19 in a clockwise direction, as shown, to maintain the brake drum 17 in pressing engagement with the brake shoe 25.

When there is no load, or very little load, on the turntable, the spring 29 pulls the brake drum 27 against the brake member 25 with maximum pressure and produces a certain load on the motor 13. As the load on the turntable is increased, the increased load causes the turntable to apply a reactive force on the idler tending to cause the idler to ride around on the rim of the turntable in a direction away from the brake shoe 25. Thus, the supporting arm 19 tends to move slightly away from the brake shoe 25 against the tension of the spring 29, thereby reducing the pressure of the brake shoe on the brake drum and cancelling out the increased load on the motor due to increase in turntable load. By proper brake design (that is, by suitably shaping the brake shoe 25 and selecting materials for the brake shoe 25 and the drum 27 to have a suitable coefficient of friction therebetween), and by properly selecting the tension of the spring 29, it is possible to maintain practically constant motor load between desired limits of turntable load. If slippage occurs at the point of contact X between the turntable rim 7 and the idler pulley 17 under turntable load, it could be compensated for by extra brake action causing extra slippage at the point of contact Y between the drive pulley 15 and the idler pulley 17 when the turntable load is light.

For a better understanding of how the pressure on the friction idler brake drum 29 is decreased by an increase in load on the turntable, and vice versa, reference is made to Figs. 3, 4 and 5. Let it be assumed that the motor drive pulley 15 rotates in a clockwise direction and, in turn, rotates the idler pulley 17 and the brake drum 27 in a counterclockwise direction, thereby causing the turntable to rotate in a clockwise direction similar to itself. As explained heretofore, if there is no load on the turntable, the only force reacting on the motor pulley 15 is that due to the friction of the brake. However, when a load is applied to the turntable, an additional reaction force is applied to the idler pulley which tends to move the idler pulley to the right, as seen in Fig. 1. A diagram of all of the forces is shown in Figs. 3, 4 and 5.

Let it be assumed, in the first case represented by Fig. 3, that the idler 17 is free to float in a

vertical direction and that the brake shoe 25 engages a brake drum 27 of the same diameter as the idler pulley 17. The force F_1 represents the motor force tending to raise the idler upwardly; F_s represents the force due to the spring 29 tending to pull the idler downwardly against the brake 25; F_b is the reactionary force of a brake 25 against the idler brake drum 27; F_f is the resultant force of the brake upon the idler in a tangential direction; and F_2 is the reactionary force upon the idler 17 due to the load on the turntable. It is the force F_2 which varies with the turntable load and reduces the braking force F_b to keep the force F_1 constant. This may be seen from the following analysis:

$$F_1 = F_2 + F_f \quad (1)$$

$$F_f = K F_b \quad (2)$$

where K = the coefficient of friction between the brake shoe 25 and the brake drum 27. For a condition of balance or equilibrium,

$$F_s = F_b + F_1 + F_2 \quad (3)$$

From Equation 3,

$$F_1 = F_s - F_b - F_2 \quad (4)$$

Substituting in Equation 4 the value of F_b derived for Equation 2,

$$F_1 = F_s - \frac{F_f}{K} - F_2 \quad (5)$$

Now, substituting in Equation 5 the value of F_f derived from Equation 1,

$$F_1 = F_s - \frac{(F_1 - F_2)}{K} - F_2 \quad (6)$$

From Equation 6, it follows that

$$F_1 + \frac{F_1}{K} = F_s + \frac{F_2}{K} - F_2 \quad (7)$$

Or,

$$\left(1 + \frac{1}{K}\right) F_1 = F_s + \left(\frac{1}{K} - 1\right) F_2 \quad (8)$$

Hence,

$$F_1 = \frac{F_s + \left(\frac{1}{K} - 1\right) F_2}{1 + \frac{1}{K}} \quad (9)$$

Assuming that $K=1$, and substituting in Equation 9, it is found that

$$F_1 = \frac{F_s}{2}$$

Similarly, if it is assumed that $K=0.5$, it is found that

$$F_1 = \frac{F_s + F_2}{3}$$

Figure 4 illustrates an arrangement like that shown in Fig. 1, namely, with the brake drum 27 having a smaller radius A than the radius B of the idler 17. The forces illustrated are the same as those in Fig. 3, the additional force F_3 being that resulting in a tangential direction on the idler pulley 17 as a result of the tangential force F_f resulting on the brake drum 27 in a tangential direction from the braking force F_b . In this alternative arrangement,

$$F_1 = F_2 + F_3 \quad (10)$$

$$F_3 = \frac{A}{B} F_f \quad (11)$$

Substituting Equation 11 in Equation 10,

$$F_1 = F_2 + \frac{A}{B} F_f \quad (12)$$

Substituting Equation 2 in Equation 12,

$$F_1 = F_2 + \frac{A}{B} (K F_b) \quad (13)$$

Now, substituting in Equation 13 the value of F_b derived from Equation 3,

$$F_1 = F_2 + \frac{A}{B} K (F_s - F_1 - F_2) \quad (14)$$

Whence,

$$F_1 = F_2 + \frac{A}{B} K F_s - \frac{A}{B} K F_1 - \frac{A}{B} K F_2 \quad (15)$$

$$\left(1 + \frac{A}{B} K\right) F_1 = \frac{A}{B} K F_s + \left(1 - \frac{A}{B} K\right) F_2 \quad (16)$$

$$\left(1 + \frac{B}{A K}\right) F_1 = F_s + \left(\frac{B}{A K} - 1\right) F_2 \quad (17)$$

$$F_1 = \frac{F_s + \left(\frac{B}{A K} - 1\right) F_2}{1 + \frac{B}{A K}} \quad (18)$$

Assuming that

$$\frac{B}{A K} = 1$$

it follows from Equation 18 that

$$F_1 = \frac{F_s}{2}$$

Similarly, where

$$\frac{B}{A K} = 2$$

then

$$F_1 = \frac{F_s + F_2}{3}$$

Also, where

$$\frac{B}{A K} = \frac{1}{2}, \quad F_1 = \frac{2F_s}{3} - \frac{F_2}{3}$$

In the foregoing illustrations, it is assumed that the brake shoe 25 is applied to the brake drum along a radius of the brake drum which is substantially 90°, or perpendicular, to a line L—L joining the center of the turntable and the center of the idler 17, as shown in Figure 1. However, the brake shoe may be applied to the brake drum at any other suitable point, for example, 45° around the brake drum from the line L—L, as shown in Fig. 5. If the angle α represents the angle between the radius along which the force F_b acts on the brake drum and the line L—L, then the force F_c shown in Fig. 5 is the component of the force F_b acting in the direction of the forces F_1 and F_2 , and

$$F_c = F_b \cos \alpha \quad (19)$$

From an inspection of Fig. 5, it will be seen that

$$F_s = F_c + F_2 + F_1 \quad (20)$$

By substituting in Equation 13, which applies equally well to Fig. 5, the value of F_b derived from Equation 19, it follows that

$$F_1 = F_2 + \left(\frac{A K}{B \cos \alpha}\right) F_c \quad (21)$$

Now, substituting the value of F_c derived from Equation 20 in Equation 21,

$$F_1 = F_2 + \left(\frac{A K}{B \cos \alpha}\right) (F_s - F_1 - F_2) \quad (22)$$

$$F_1 = F_2 \left(\frac{A K}{B \cos \alpha}\right) F_s - \left(\frac{A K}{B \cos \alpha}\right) F_1 - \left(\frac{A K}{B \cos \alpha}\right) F_2 \quad (23)$$

Solving for F_1 , it is found that

$$F_1 = \frac{\left(\frac{A K}{B \cos \alpha}\right) F_s + \left(1 - \frac{A K}{B \cos \alpha}\right) F_2}{1 + \frac{A K}{B \cos \alpha}} \quad (24)$$

Assuming that

$$\frac{A K}{B \cos \alpha} = 1$$

then

$$F_1 = \frac{F_s}{2}$$

If

$$\frac{A K}{B \cos \alpha} = \frac{1}{2}$$

then

$$F_1 = \frac{2F_s + 2F_2}{3}$$

On the other hand, where

$$\frac{A K}{B \cos \alpha} = \frac{3}{4}, \quad F_1 = \frac{F_s - F_2}{2}$$

From the foregoing analyses, it will be apparent that by a suitable relation between the coefficient of friction between the brake shoe 25 and the brake drum 27 and the radii of the brake drum 27 and the idler pulley 17, the load on the motor 13 can be held constant with the turntable load or can be made to increase or decrease in proportion to, or as a function of, the turntable load. In one arrangement which was constructed and tested, the idler 17 was 2½ inches in diameter and had a brake drum 27 of cylindrical form and a diameter of approximately 2½ inches. The brake shoe 25 was made of poplar and was arranged to press against the drum as illustrated in Fig. 5, or about 45° around the drum from the line L—L. In this construction, there was a reduction of speed of 0.455 percent to 0.3 percent when the turntable load was increased from 0 to 56 inch ounces. This may be contrasted with a change of 2.53 percent upon a change of turntable load from 0 to 60 inch ounces when the brake member 25 was not used. In another form of the invention, a chrome leather brake was used and arranged as in Fig. 5. This arrangement showed a change of speed of from 0.6 percent to 0.3 percent over a turntable load range of from 0 to 60 inch ounces. Using a brake drum with a 60° V groove and a chrome leather brake fitting the V groove of the drum and set at approximately 90° to the line L—L, as shown in Fig. 1 and as illustrated by Fig. 4, there was a loss of speed of only 0.5 percent as the turntable load increased from 0 to 56 inch ounces.

The invention heretofore described may not only be employed to compensate for added load on the turntable to thereby keep the load on the motor constant, but it is also possible to obtain over-compensation. Thus, by using a 30° V groove brake drum and a poplar brake set at 90° to the line L—L, the speed of the turntable actu-

ally increased about 1 percent when the load of the turntable was increased from 0 to 60 inch ounces.

From the foregoing description it will be apparent to those skilled in the art that I have provided a novel power transmitting mechanism by means of which the load on the motor may be maintained constant with variations in load on the driven member. Although I have shown and described several arrangements embodying one form of my invention, it will be apparent to those skilled in the art that many other variations are possible. I therefore do not wish to be limited except insofar as is made necessary by the prior art and by the spirit of the appended claims.

I claim as my invention:

1. In combination, a driving member, a driven member subject to variations in load, an idler interposed between said members for transferring torque therebetween, braking means associated with said idler for applying a restraining force thereto, and means mounting said idler for movement relative to said driven member and also relative to said braking means in response to variations in load on said driven member, said load variations causing said idler to move relative to said driven member and thereby to effect movement of said idler relative to said braking means for varying said restraining force as a function of the load on said driven member.

2. In combination, a driving member, a driven member subject to variations in load, an idler interposed between said members for transferring torque therebetween, braking means associated with said idler for applying a restraining force thereto, and means floatingly supporting said idler relative to said braking means whereby said idler is adapted to vary its contact with said braking means in accordance with variations in load on said driven member to thereby vary said restraining force as a function of said load.

3. In combination, a driving member, a driven member subject to variations in load, an idler interposed between said members for transferring torque therebetween, said idler including a brake drum, a brake member, means floatingly supporting said idler relative to said brake member, and means constraining said idler into position such that said brake drum is in pressing engagement with said brake member whereby said brake member is adapted to apply a restraining force to said idler, said brake drum being adapted by reason of the floating support of said idler to vary its engagement with said brake member in response to variations in load on said driven member to thereby correspondingly vary said restraining force as a function of said load.

4. In a phonograph, the combination of a turntable subject to variations in load, a motor including a driving pulley, a floating friction idler interposed between and having engagement with said driving pulley and the rim of said turntable, said idler including a brake drum, a brake member, and means constraining said idler into pressing engagement with said brake member whereby said brake member is adapted to apply a restraining force to said idler, said brake drum being adapted by reason of said floating idler to vary its engagement with said brake member in response to variations in load on said turntable to thereby correspondingly vary said restraining force as a function of said load.

5. In a phonograph, the combination of a turntable subject to variations in load, a motor

including a driving pulley, a friction idler interposed between and having engagement with said driving pulley and the rim of said turntable, said idler including a brake drum, a brake member, means floatingly supporting said idler relative to said brake member, and means constraining said supporting means into position such that said brake drum is in pressing engagement with said brake member whereby said brake member is adapted to apply a restraining force to said idler, said brake drum being adapted by reason of the floating support of said idler to vary its engagement with said brake member in response to variations in load on said turntable to thereby correspondingly vary said restraining force as a function of said load.

6. In a phonograph, the combination of a turntable subject to variations in load, a motor including a driving pulley, a friction idler interposed between and having engagement with said pulley and the rim of said turntable, said idler including a brake drum, a brake member, a pivotally mounted supporting arm carrying said idler in floating relation to said brake member, and spring means connected to said arm and arranged to constrain said arm to a position such that said brake drum is in pressing engagement with said brake member whereby said brake member is adapted to apply a restraining force to said idler, said brake drum being adapted by reason of said floating idler to vary its engagement with said brake member in response to variations in load on said turntable to thereby correspondingly vary said restraining force as a function of said turntable load.

7. The invention set forth in claim 6 characterized in that said brake member is so located with respect to said brake drum that it engages said brake drum at a point on the circumference thereof from which a radius thereof is at an angle to a line joining the centers of said turntable and said brake drum.

8. The invention set forth in claim 6 characterized in that said brake member is so located with respect to said brake drum that it engages said brake drum at a point on the circumference thereof from which a radius thereof is at an angle of substantially 45° to a line joining the centers of said turntable and said brake drum.

9. The invention set forth in claim 6 characterized in that said brake member is so located with respect to said brake drum that it engages said brake drum at a point on the circumference thereof from which a radius thereof is at an angle of substantially 90° to a line joining the centers of said turntable and said brake drum.

10. The invention set forth in claim 6 characterized in that said idler and said brake drum are concentric and characterized further in that said idler has a different diameter than said drum.

11. The invention set forth in claim 6 characterized in that said idler and said brake drum are concentric, characterized further in that said idler has a different radius than said drum, and characterized still further in that said brake member is so located with respect to said brake drum that it engages said brake drum at a point on the circumference of said drum from which a radius thereof is at an angle to a line joining the centers of said turntable and said drum.

12. The invention set forth in claim 6 characterized in that said idler and said brake drum are concentric, characterized further in that said idler has a different radius than said drum, char-

acterized further in that said brake member is so located with respect to said brake drum that it engages said brake drum at a point on the circumference of said drum from which a radius thereof is at an angle to a line joining the centers of said turntable and said drum, and characterized still further in that the force applied by said driving pulley to said idler is given by the equation

$$F_1 = \frac{\left(\frac{AK}{B \cos \alpha}\right)F_s + \left(1 - \frac{AK}{B \cos \alpha}\right)F_2}{1 + \frac{AK}{B \cos \alpha}}$$

10

where

F_1 = force applied by said driving pulley to said idler,

F_2 = force of reaction of said turntable on said idler due to said turntable load,

F_s = force of said spring means on said supporting arm tending to maintain engagement of said idler brake drum with said brake member,

A = radius of said brake drum,

B = radius of said idler, and

α = said angle.

JOSEPH L. UNDERHILL.
